**CALL MECHANISM FOR AUTOMATIC
TELEPHONE DIALERS**

Thomas W. MacKenzie, Cranford, N. J.

Application December 2, 1955, Serial No. 550,629

14 Claims. (Cl. 179—90)

This invention relates to what are known as automatic telephone dialers, where one of a number of keys are manually operated to automatically call a telephone number, thereby dispensing with the need of dialing the number as with the conventional dial telephones.

More particularly, the invention deals with the call actuating mechanism of dialers of this type and kind employing a simple and economical type of key construction and simple switch and switch operating means for pulsing the number through the control means of the key.

Still more particularly, the invention deals with a mechanism of the character described, wherein a standard key blank can be employed and the same simply and easily fashioned in producing thereon any desired number to be called in the use of the key in the automatic dialer.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a diagrammatic face view of the switch mechanism of a dialer made according to my invention, showing the parts in normal inoperative position.

Fig. 2 is a partial detail section, substantially on the line 2—2 of Fig. 1.

Fig. 3 is a diagrammatic side view of a key in the normal inoperative position with associated operating mechanism illustrated in section and illustrating a top fingerpiece portion of the key in section.

Fig. 4 is a view, generally similar to Fig. 3, omitting parts of the construction and showing the key in the fully depressed position.

Fig. 5. is a view, similar to Fig. 4, showing the key in the call pulsing position; and

Fig. 6 is a diagrammatic view of part of the wiring diagram illustrating one of the key circuits in operative pulsing position.

My present invention deals with automatic telephone dialers, generally of the type and kind disclosed in my prior Patent Number 2,407,889, granted September 17, 1946, and deals primarily with the call mechanism of dialers of this type and kind, that is to say, the manually actuated key and the switches controlling the circuits of the two banks of keys which are usually employed in dialers of the kind under consideration.

In Fig. 1 of the drawing, I have diagrammatically shown the switch end portion of a dialer employing two left and right side spring tensioned gear shafts 10 and 11 suitably supported upon the end wall 12 of the dialer mechanism as a whole. The shafts 10 and 11 protrude beyond the wall 12 and have adjustably fixed thereto switch actuating elements 13 and 14 composed of insulating material. The elements have projecting stepped lugs 15 and 16, one of which is clearly noted in Fig. 2 of the drawing, to operatively engage contacts 17 and 18 and 17', 18', respectively, to normally break

2

the circuit between these contacts, thus rendering the dialer inoperative. However, in the rotation of either one of the shafts 10 and 11, as later described, the element 13 or 14 will be moved into inoperative position 5 to close the circuit through the switches. In Fig. 1 of the drawing, the element 13 is indicated in inoperative position in dotted lines, thus completing the circuit through the contacts 17 and 18 and this same dotted position is diagrammatically illustrated in the wiring diagram of Fig. 6, the contacts 17 and 18 being identified in this diagram.

Mounted on shafts 19 and 20 outwardly of the shafts 10 and 11 are pulsing pawls 21 and 22, respectively, which operate upon switch contacts 23 and 24 in the pulsing operation of the circuit, in other words, in opening and closing the circuit between the contacts 23, 24 and associate contacts 23', 24'. These contacts are also diagrammatically illustrated in the wiring diagram of Fig. 6 and it will appear that the contacts are normally 10 closed and, with the left side of the circuit in operation, the contacts 23, 23' are shown open to diagrammatically illustrate the pulsing operation of the circuit.

The shafts 19 and 20, within the casing of the dialer, are of an irregular cross-sectional form, one of these 15 shafts, the shaft 19, being shown in Fig. 3 of the drawing. One side of the shaft has right angle surfaces, as at 25; whereas, the other side has similar surfaces 26, cutaway, as seen at 27, and fashioned to form a pulsing flange 28, the lower surface 29 of which is preferably 20 radial with respect to the axis of the shaft. As both shafts 19 and 20 are of the same construction, only one shaft is shown in detail and it will be understood that the shaft 20 is of the same structure. With this 25 thought in mind, again only one key 30 is illustrated, that is to say, one key in the row of keys that will be disposed in the left hand side of the dialer. The righthand 30 rows of keys are not shown, but these would be arranged adjacent the shaft 20, as will be apparent.

From a consideration of Fig. 3 of the drawing, it will 35 appear that only one of the gear shafts are shown, namely the shaft 10, but here again, the shaft 11 will be of the same construction. One side of the key 30 has a long rack 31 operatively engaging the teeth of the elongated gear portion 10' of the shaft 10. The same side edge of the key, at its upper portion, has a conical type of recess 32 for receiving a yieldable lock pin 33 for normally supporting the key in raised inoperative position. When the key is depressed, this 40 pin 33 is moved outwardly, as noted in Figs. 4 and 5, and when one key is depressed, other keys are locked against movement. However, as this control forms no part of the present invention and is disclosed in the prior 45 patent, no further detailed reference thereto will be made.

The other side edge of the key 30 has, at its lower 50 portion, a recess 34 and said side edge adjacent the recess 32 has a recess 35. Between the recesses 34 and 35, the last named side edge has a pulsing section 36 which, in producing the keys, is cut with a predetermined 55 number of continuous teeth, part of these teeth being shown at 37 in Fig. 5. Thus, in producing a key for calling a predetermined telephone number, parts of the teeth of the section 36 are removed, as indicated at 38, thereby producing spaced number pulsing units 39, and, 60 in Fig. 5 of the drawing in illustrating one type of key, the cutouts, at 38, are such as to produce a pulsing call number MU (Murray Hill) 6-8800. In other words, 65 the number of teeth remaining in each unit 39 will actuate the pawl 21 so as to transmit through the switch 23, first six impulses, then eight, then six, then eight, then eight, then ten and then ten.

Normally, the element 28 is disposed in the recess 34

and, as the key 30 is moved downwardly in the operation of placing a call, the element 28 is moved downwardly, which raises the pawl 21. Upon completing the downward movement of the key, the element 28 moves into the recess 35, as noted in Fig. 4 of the drawing, after which, the spring tensioned gear 10' operates to return the key to normal position, that is to say, to move the same upwardly; whereupon, the teeth of the various pulsating units 39 intermittently actuate the element 28, thereby actuating the pawl 21 to break the circuit between contacts 23, 23' in pulsing the call.

The foregoing description is all centered around the single key and the mechanism associated therewith. Considering Fig. 1 of the drawing, it will appear that springs 40, 41 are coupled with the pawls 21 and to a common post 42 on the wall 12, the springs operating to automatically remove the pawls from the contacts 23, 24 after said contacts have been actuated by the pawls through the medium of the elements 28.

The call operation, that is to say, the pulsing operation, is very quick and much faster than normal manual operation of the conventional dialer of a telephone. It will be understood that the key 30 must be fully depressed before a call can be pulsed, as the element 28, in engaging the teeth 37, would normally lock the key against upward movement. This will be apparent from the position that the element 28 would assume when the key 30 is moved downwardly. In other words, the element 28 would be directed downwardly rather than upwardly, as noted in Fig. 5 of the drawing.

The upper end portion of the key 30 has notches or recesses 43 on opposed edges thereof, with which a fingerpiece casing 44 is suitably coupled, the key being held against displacement from the casing 44 by a lock element 45. At the upper part of the casing is a characterized plate 46 bearing the name of an individual, firm or station to be called.

At this time, it is pointed out that dialers of the character described will have keys suitable for calling numbers which are called frequently and the characterized strip or plate 46 can have thereon any marking to identify the individual or telephone number to be called. In the use of the dialer, all that is necessary is to remove the receiver of a telephone in the usual manner and simply depress the key of the number which is desired; whereupon, the number is automatically called through the pulsing operation transmitted to either of the switches 23, 23' or 24, 24'. Upon completing the call, the key 30 returns to the normal inoperative position shown in Fig. 3 of the drawing.

Fig. 4 shows the fully depressed position of the key, preparatory to performing the pulsing operations. Fig. 5 shows the key in the operation of pulsing a call. However, no specific showing is made of the position of the shaft 19 and the element 28 thereon in moving the key from the inoperative position of Fig. 3 to the lowered position of Fig. 4.

No showing of the circuit wires coupled with the various switches diagrammatically shown in Fig. 1 of the drawing is made, as this will be clear from the diagrammatic wiring diagram of Fig. 6 of the drawing. As previously stated, normally the circuit is closed through the switches 23, 23'; 24, 24' and the circuit through the switches 17, 18; 17', 18' is normally opened and held so by the elements 13 and 14. However, when a key in one side of the dialer such, for example, as the lefthand side is operated, then the circuit is closed through switches 17 and 18 and the switches 23, 23' are in position for pulsing the call. In the same manner, if a key of the righthand bank of keys is actuated, then the circuit through switches 17 and 18 will remain open, circuit through the contacts 23, 23' will be closed, the circuits through contacts 17', 18' will be completed and contacts 24, 24' will be in position for pulsing a call.

From a standpoint of production, it will be under-

stood that a single key blank is produced, this blank being fashioned to dial any telephone number by simply removing portions of the teeth of the section 36, as for example, at 38 in Fig. 5 of the drawing, to specifically characterize the call units 39. The length of the section 36 will be sufficient to dial any telephone number.

In some specific instances, shorter or longer sections 36 can be employed in the key blanks. However, the key illustrated is designed for the more conventional uses.

It will be understood that, when one of the keys is actuated, and the pulsing bar or its element 28 is in the upwardly tilted position, as noted in Fig. 5 of the drawing, no other key engaging 28 can be depressed, it being understood in this connection, that the element 28 of the shaft or bar 19 extends the full length of the shaft to operatively engage all keys in a single bank of keys.

It will be understood that the pawls 21 and 22, which are adjustably fixed upon the ends of the shafts 19 and 20, be composed of insulating material, such as fibre, as will also the actuating elements 13 and 14.

Having fully described my invention, what I claim as new and desire to secure by Letters Patent is:

1. In telephone dialers of the class described, a call actuating mechanism comprising a plurality of call keys, each of said keys having a gear rack edge and an opposed tooth-like edge having pulsing sections, a pair of spaced shafts having longitudinal gear portions, said keys being spaced longitudinally of said gear portions with the gear racks of said teeth in position to operatively engage said gear portions, another pair of shafts spaced from the first shafts and having longitudinally extending pulsing elements adapted to operatively engage said pulsing sections, said first shafts being spring tensioned and having switch actuating members of insulating material on one end thereof, two pairs of contacts operated by said last named members and normally supporting the contacts in open circuit position, the corresponding end of the second named shafts having insulated pulsing pawls mounted thereon, a pair of pulsing contacts adjacent each pawl, and one of the contacts of each pair being actuated by the adjacent pawl in intermittently breaking circuit through the last named contacts in pulsing a predetermined call number by movement of one of the pulsing sections of a key over the pulsing element of the shaft to which said pawl is fixed.

2. In telephone dialers of the class described, a call actuating mechanism comprising a plurality of call keys, each of said keys having a gear rack edge and an opposed tooth-like edge having pulsing sections, a pair of spaced shafts having longitudinal gear portions, said keys being spaced longitudinally of said gear portions with the gear racks of said teeth in position to operatively engage said gear portions, another pair of shafts spaced from the first shafts and having longitudinally extending pulsing elements adapted to operatively engage said pulsing sections, said first shafts being spring tensioned and having switch actuating members of insulating material on one end thereof, two pairs of contacts operated by said last named members and normally supporting the contacts in open circuit position, the corresponding end of the second named shafts having insulated pulsing pawls mounted thereon, a pair of pulsing contacts adjacent each pawl, one of the contacts of each pair being actuated by the adjacent pawl in intermittently breaking circuit through the last named contacts in pulsing a predetermined call number by movement of one of the pulsing sections of a key over the pulsing element of the shaft to which said pawl is fixed, and the circuit through one pair of the first named contacts being closed by operation of the switch actuating member on one of the first named shafts in the depression of a key in setting the mechanism to dialing operation.

3. In telephone dialers of the class described, a call

actuating mechanism comprising a plurality of call keys, each of said keys having a gear rack edge and an opposed tooth-like edge having pulsing sections, a pair of spaced shafts having longitudinal gear portions, said keys being spaced longitudinally of said gear portions with the gear racks of said teeth in position to operatively engage said gear portions, another pair of shafts spaced from the first shafts and having longitudinally extending pulsing elements adapted to operatively engage said pulsing sections, said first shafts being spring tensioned and having switch actuating members of insulating material on one end thereof, two pairs of contacts operated by said last named members and normally supporting the contacts in open circuit position, the corresponding end of the second named shafts having insulated pulsing pawls mounted thereon, a pair of pulsing contacts adjacent each pawl, one of the contacts of each pair being actuated by the adjacent pawl in intermittently breaking circuit through the last named contacts in pulsing a predetermined call number by movement of one of the pulsing sections of a key over the pulsing element of the shaft to which said pawl is fixed, the circuit through one pair of the first named contacts being closed by operation of the switch actuating member on one of the first named shafts in the depression of a key in setting the mechanism to dialing operation, the second edge of each key having, beyond the pulsing section, recesses facilitating swinging movement of the pulsating elements in positioning said elements for pulsing movement over the sections of the keys, a fingerpiece portion detachably coupled with the upper end of each key, and said fingerpiece portion supporting an identifying strip characterizing the particular telephone number called by the key.

4. In telephone dialers of the class described, a call actuating mechanism comprising a plurality of call keys, each of said keys having a gear rack edge and an opposed tooth-like edge having pulsing sections, a pair of spaced shafts having longitudinal gear portions, said keys being spaced longitudinally of said gear portions with the gear racks of said teeth in position to operatively engage said gear portions, another pair of shafts spaced from the first shafts and having longitudinally extending pulsing elements adapted to operatively engage said pulsing sections, said first shafts being spring tensioned and having switch actuating members of insulating material on one end thereof, two pairs of contacts operated by said last named members and normally supporting the contacts in open circuit position, the corresponding end of the second named shafts having insulated pulsing pawls mounted thereon, a pair of pulsing contacts adjacent each pawl, one of the contacts of each pair being actuated by the adjacent pawl in intermittently breaking circuit through the last named contacts in pulsing a predetermined call number by movement of one of the pulsing sections of a key over the pulsing element of the shaft to which said pawl is fixed, the circuit through one pair of the first named contacts being closed by operation of the switch actuating member on one of the first named shafts in the depression of a key in setting the mechanism to dialing operation, and means comprising a lock pin operatively engaging a recess in the first side edge of said key for retaining the key normally in inoperative position.

5. In telephone dialers of the class described, a call actuating mechanism comprising a plurality of call keys, each of said keys having a gear rack edge and an opposed tooth-like edge having pulsing sections, a pair of spaced shafts having longitudinal gear portions, said keys being spaced longitudinally of said gear portions with the gear racks of said teeth in position to operatively engage said gear portions, another pair of shafts spaced from the first shafts and having longitudinally extending pulsing elements adapted to operatively engage said pulsing sections, said first shafts being spring tensioned and having switch actuating members of insulating material on one end thereof, two pairs of contacts operated by said last named members and normally supporting the contacts in open circuit position, the corresponding end of the second named shafts having insulated pulsing pawls mounted thereon, a pair of pulsing contacts adjacent each pawl, one of the contacts of each pair being actuated by the adjacent pawl in intermittently breaking circuit through the last named contacts in pulsing a predetermined call number by movement of one of the pulsing sections of a key over the pulsing element of the shaft to which said pawl is fixed, the circuit through one pair of the first named contacts being closed by operation of the switch actuating member on one of the first named shafts in the depression of a key in setting the mechanism to dialing operation, the second edge of each key having, beyond the pulsing section, recesses facilitating swinging movement of the pulsating elements in positioning said elements for pulsing movement over the sections of the keys.

5. In telephone dialers of the class described, a call actuating mechanism comprising a plurality of call keys, each of said keys having a gear rack edge and an opposed tooth-like edge having pulsing sections, a pair of spaced shafts having longitudinal gear portions, said keys being spaced longitudinally of said gear portions with the gear racks of said teeth in position to operatively engage said gear portions, another pair of shafts spaced from the first shafts and having longitudinally extending pulsing elements adapted to operatively engage said pulsing sections, said first shafts being spring tensioned and having switch actuating members of insulating material on one end thereof, two pairs of contacts operated by said last named members and normally supporting the contacts in open circuit position, the corresponding end of the second

named shafts having insulated pulsing pawls mounted thereon, a pair of pulsing contacts adjacent each pawl, one of the contacts of each pair being actuated by the adjacent pawl in intermittently breaking circuit through the last named contacts in pulsing a predetermined call number by movement of one of the pulsing sections of a key over the pulsing element of the shaft to which said pawl is fixed, the circuit through one pair of the first named contacts being closed by operation of the switch actuating member on one of the first named shafts in the depression of a key in setting the mechanism to dialing operation, the second edge of each key having, beyond the pulsing section, recesses facilitating swinging movement of the pulsating elements in positioning said elements for pulsing movement over the sections of the keys, a fingerpiece portion detachably coupled with the upper end of each key, and said fingerpiece portion supporting an identifying strip characterizing the particular telephone number called by the key.

6. In telephone dialers of the class described, a call actuating mechanism comprising a plurality of call keys, each of said keys having a gear rack edge and an opposed tooth-like edge having pulsing sections, a pair of spaced shafts having longitudinal gear portions, said keys being spaced longitudinally of said gear portions with the gear racks of said teeth in position to operatively engage said gear portions, another pair of shafts spaced from the first shafts and having longitudinally extending pulsing elements adapted to operatively engage said pulsing sections, said first shafts being spring tensioned and having switch actuating members of insulating material on one end thereof, two pairs of contacts operated by said last named members and normally supporting the contacts in open circuit position, the corresponding end of the second named shafts having insulated pulsing pawls mounted thereon, a pair of pulsing contacts adjacent each pawl, one of the contacts of each pair being actuated by the adjacent pawl in intermittently breaking circuit through the last named contacts in pulsing a predetermined call number by movement of one of the pulsing sections of a key over the pulsing element of the shaft to which said pawl is fixed, all of the keys being formed from common key blanks, the pulsing section of each blank comprising a plurality of equally spaced teeth, and part of the teeth being removed in producing, on the section, a predetermined arrangement of spaced pulsing operations defining a specific telephone call number.

7. In telephone dialers of the class described, a call actuating mechanism comprising a plurality of call keys, each of said keys having a gear rack edge and an opposed tooth-like edge having pulsing sections, a pair of spaced shafts having longitudinal gear portions, said keys being spaced longitudinally of said gear portions with the gear racks of said teeth in position to operatively engage said gear portions, another pair of shafts spaced from the first shafts and having longitudinally extending pulsing elements adapted to operatively engage said pulsing sections, said first shafts being spring tensioned and having switch actuating members of insulating material on one end thereof, two pairs of contacts operated by said last named members and normally supporting the contacts in open circuit position, the corresponding end of the second named shafts having insulated pulsing pawls mounted thereon, a pair of pulsing contacts adjacent each pawl, one of the contacts of each pair being actuated by the adjacent pawl in intermittently breaking circuit through the last named contacts in pulsing a predetermined call number by movement of one of the pulsing sections of a key over the pulsing element of the shaft to which said pawl is fixed, and said pawls having tensional means normally supporting said contacts in closed circuit position.

8. In telephone dialers of the class described, a call actuating mechanism comprising a plurality of call keys,

each of said keys having a gear rack edge and an opposed tooth-like edge having pulsing sections, a pair of spaced shafts having longitudinal gear portions, said keys being spaced longitudinally of said gear portions with the gear racks of said teeth in position to operatively engage said gear portions, another pair of shafts spaced from the first shafts and having longitudinally extending pulsing elements adapted to operatively engage said pulsing sections, said first shafts being spring tensioned and having switch actuating members of insulating material on one end thereof, two pairs of contacts operated by said last named members and normally supporting the contacts in open circuit position, the corresponding end of the second named shafts having insulated pulsing pawls mounted thereon, a pair of pulsing contacts adjacent each pawl, one of the contacts of each pair being actuated by the adjacent pawl in intermittently breaking circuit through the last named contacts in pulsing a predetermined call number by movement of one of the pulsing sections of a key over the pulsing element of the shaft to which said pawl is fixed, said pawls having tensional means normally supporting said contacts in closed circuit position, and that part of the second named shafts including said pulsing elements being of irregular cross-sectional form and the shafts at opposed sides of said elements being cutaway to provide free action of the elements with respect to the pulsing sections of said keys.

9. In telephone dialers of the class described, a call actuating mechanism comprising a plurality of call keys, each of said keys having a gear rack edge and an opposed tooth-like edge having pulsing sections, a pair of spaced shafts having longitudinal gear portions, said keys being spaced longitudinally of said gear portions with the gear racks of said teeth in position to operatively engage said gear portions, another pair of shafts spaced from the first shafts and having longitudinally extending pulsing elements adapted to operatively engage said pulsing sections, said first shafts being spring tensioned and having switch actuating members of insulating material on one end thereof, two pairs of contacts operated by said last named members and normally supporting the contacts in open circuit position, the corresponding end of the second named shafts having insulated pulsing pawls mounted thereon, a pair of pulsing contacts adjacent each pawl, one of the contacts of each pair being actuated by the adjacent pawl in intermittently breaking circuit through the last named contacts in pulsing a predetermined call number by movement of one of the pulsing sections of a key over the pulsing element of the shaft to which said pawl is fixed, said pawls having tensional means normally supporting said contacts in closed circuit position, the pulsing elements of said second named shafts comprising outwardly extending longitudinal flanges, and at least one surface of each flange extending radially with respect to the axis of the shafts.

10. A call key for automatic telephone dialers of the class described, said key comprising an elongated member having opposed side edges, one edge having a plurality of longitudinally and equally spaced continuously uninterrupted gear teeth to form a gear rack thereon, the other side edge having an elongated pulsing section defined by equally spaced teeth, portions of the teeth being removed at intervals to define, on said section, a plurality of call units, the number of teeth in each unit defining the number of pulsing operations in transmitting through a telephone system a predetermined telephone number, and the upper end of the key having a detachable fingerpiece portion.

11. A call key for automatic telephone dialers of the class described, said key comprising an elongated member having opposed side edges, one edge having a plurality of longitudinally spaced gear teeth to form a gear rack thereon, the other side edge having an elongated pulsing section defined by equally spaced teeth, portions of the teeth being removed at intervals to define, on

said section, a plurality of call units, the number of teeth in each unit defining the number of pulsing operations in transmitting through a telephone system a predetermined telephone number, the upper end of the key having a detachable fingerpiece portion, and the second named edge of the key above and below said pulsing section having elongated recesses.

12. A call key for automatic telephone dialers of the class described, said key comprising an elongated member having opposed side edges, one edge having a plurality of longitudinally spaced gear teeth to form a gear rack thereon, the other side edge having an elongated pulsing section defined by equally spaced teeth, portions of the teeth being removed at intervals to define, on said section, a plurality of call units, the number of teeth in each unit defining the number of pulsing operations in transmitting through a telephone system a predetermined telephone number, the upper end of the key having a detachable fingerpiece portion, the second named edge of the key above and below said pulsing section having elongated recesses, and the first named edge portion of the key, above the gear rack, having a substantially conical recess adapted to receive a lock pin in positioning the key in a dialer.

13. In automatic telephone dialers of the character described, wherein two banks of keys are arranged in the dialer, each key having a gear rack edge and a pulsing section edge, a spring tensioned elongated gear shaft adjacent the gear rack edge of each key, another shaft, at the second named edge of each key, the last named shafts having longitudinally arranged and radially extending pulsing elements adapted to operatively engage the pulsing section of said keys, means normally supporting the keys in raised inoperative position with respect to said shafts, two pairs of switch contacts arranged adjacent one end portion of the first named shafts, insulating means fixed to said ends of said shafts operatively engaging said contacts to normally support the contacts in open circuit position, two other pairs of contacts arranged adjacent the corresponding ends of the second named shafts and normally in closed circuit position, pawls on said ends of the second named shafts operatively engaging the last named switches to intermittently break the circuit through said switches in passage of the pulsing element of said shafts over the pulsing sections of said keys, and tensional means controlling operation of said pawls, whereby, in the actuation of a key to call a predetermined telephone number, one of the first named shafts is rotated to close the circuit through one pair of the first named switch contacts and actuate the adjacent element to position the same for transmitting call pulsing operations in reverse movement of the key by engagement of the gear with the rack of said key.

14. In automatic telephone dialers of the character described, wherein two banks of keys are arranged in the dialer, each key having a gear rack edge and a pulsing section edge, a spring tensioned elongated gear shaft adjacent the gear rack edge of each key, another shaft, at the second named edge of each key, the last named shafts having longitudinally arranged and radially extending pulsing elements adapted to operatively engage the pulsing section of said keys, means normally supporting the keys in raised inoperative position with respect to said shafts, two pairs of switch contacts arranged adjacent one end portion of the first named shafts, insulating means fixed to said ends of said shafts operatively engaging said contacts to normally support the contacts in open circuit position, two other pairs of contacts arranged adjacent the corresponding ends of the second named shafts and normally in closed circuit position, pawls on said ends of the second named shafts operatively engaging the last named switches to intermittently break the circuit through said switches in passage of the pulsing element of said shafts over the pulsing sections of said keys, tensional means controlling operation of said pawls, whereby, in the actuation of a key to call a pre-

determined telephone number, one of the first named shafts is rotated to close the circuit through one pair of the first named switch contacts and actuate the adjacent element to position the same for transmitting call pulsing operations in reverse movement of the key by engagement of the gear with the rack of said key, and said pulsing element operatively engaging the pulsing sections of adjacent keys of a bank locking said adjacent keys

10
against operation while the pulsing section of one key is operatively engaging said pulsing element.
